UNITED STATES PATENT OFFICE.

CHARLES LOFFMAN, OF LOS ANGELES, CALIFORNIA, ASSIGNOR TO ROBERTI BROS., OF LOS ANGELES, CALIFORNIA, A CORPORATION OF CALIFORNIA.

PORTABLE FOLDING BED.

Application filed September 30, 1925. Serial No. 59,570.

As may be inferred from the above designation, this invention relates to beds such as are adapted to stand upright in a closet, or the like, when not in use, and to be moved out, upon a truck comprised in the bed organization, into any desired location, before the bed frame, carrying springs and a mattress, is swung into a substantially horizontal position of use.

It being a common fault of beds of the general character referred to, each comprising a castered truck upon which a bed frame is pivoted, that they are liable to be tipped by an unskillful effort to swing the bed frame from an upright position toward a horizontal position (the danger referred to being especially serious if the organization happens to be supported by a floor which is not perfectly level, or if the mentioned movement is hastily executed) it is a primary object of this invention to provide improved and genuinely automatic means, preferably comprising an arm mounted on said truck for movement in a horizontal plane and a cam on the mentioned bed frame, effective to provide an enlarged base for the described organization during the lowering of the mentioned bed frame toward a horizontal position; and advantageous embodiments of my invention may comprise bed frames equipped with springs of a somewhat special and improved type, as hereinafter described.

Other objects of my invention may be best appreciated from the following description of an advantageous embodiment thereof, taken in connection with the appended claims and the accompanying drawings, in which

Fig. 1 may be regarded as a side elevational view of a bed organization illustrating one form of my invention, parts being broken away, and the horizontal position to which the bed frame may be swung for actual use being suggested by dot-and-dash lines.

Fig. 2 is a horizontal sectional view, with parts broken away, this view being taken in a plane such as that indicated by the line 2-2 of Fig. 1.

Fig. 3 is a vertical section, taken substantially as indicated by the line 3-3 of Fig. 2, with parts broken away.

Fig. 4 is a perspective sectional detail view, with parts broken away, taken sub-

stantially as indicated by the arrows 4 of Figs. 2 and 3.

Referring to the details of that specific embodiment of my invention chosen for the purpose of illustration, 11 may be a substantially rigid truck, shown as supported by casters 12 near the respective corners thereof and as comprising a substantially horizontal frame which includes longer horizontal frame elements 13, 13', connected by shorter outside horizontal elements 14, 14' and by intermediate horizontal elements 15, 15', the said truck optionally comprising also an upright and overarching frame element 16, which may occupy a position, and be characterized by an appearance, rendering the same comparable to the head-board of an ordinary bed.

As shown, the outside elements of the described truck frame are formed from angle iron, and the intermediate horizontal elements 15, 15' may be formed of a similar rolled stock or from a shallow channel stock, only the overarching element 16 being shown as formed of a rectangular tubular stock, suitably bent; and the described truck, or its equivalent, may comprise also substantially vertical pivot posts 17, 17', shown as secured to the shorter horizontal frame elements 14, 14' and as reinforced by braces 18, 18' extending downward therefrom toward the front of the mentioned truck frame,—the use of substantially horizontal diagonal braces 19, extending across some or all of the corners of the frame 11, being optional and dependent upon the dimensions and consequent strength of the angle stock, or its equivalent, employed in the construction of said truck.

Coming now to the more unique features of my invention, I show a horizontally movable member or base-enlarging brace 20 as pivoted at 21 to one of the intermediate horizontal elements 15, 15', in such manner as to provide a lever whose longer arm 22 may carry, at or near its outer end, a rolling or gliding element 23, and whose inner and shorter end 24 may have a configuration adapting it to be moved in a horizontal plane by means such as a suitable cam or cams provided on the frame of a bed, supported by the mentioned posts 17, 17'. If desired, the inner end or shorter arm 24 of the mentioned lever may be provided with resilient means such as a tension spring 25, tending

to throw the longer and outer arm 22 from an inner position, in which it is shown in full lines, to an outer position such as that in which it is shown in dot-and-dash lines; 5 and, if desired, the longer truck frame element 13', or its equivalent, may be provided with means such as a bearing ball 26, yieldably or otherwise secured therein in any preferred manner and adapted to enter an 10 aperture or cup 27 in the arm 22, the inter-engagement between the ball 26 and the socket 27, or their equivalents being effective releasably to hold the arm 22 in its indicated outer position, whenever the same is advanced thereto by means such as the cams hereinafter described, or the spring 25.

Supporting one end thereof, as the head end, by means such as pivots 28 at the upper ends of the posts 17, I may secure to the 20 described truck, or its equivalent, a bed frame comprising usual parallel side elements 29, 29', and transversely extending end elements 30, the side elements 29, 29' being shown as provided with brackets 31, 25 31', through which the pivots 28, 28' extend. In order to provide a resilient support for a mattress extending parallel with the plane of the mentioned bed frame, or its equivalent, I may employ suitable springs, preferably of the novel type herein illustrated, 30 securing a mattress relatively thereto by any preferred means, as by means including a special mattress stop comprising a bent tubular element 32, shown as secured at its ends to the mentioned end element 30.

Between the rebent end portions 34, 34' of the tubular element 32 I may secure a reinforcing element 35, shown as an angle bar extending parallel with the elements 30 40 and as having welded thereto minor reinforcing bars 36, extending to the intermediate portion of the tubular element 32 and providing an end stop for any mattress supported upon the spring organization hereinafter described, or its equivalent.

To assist in shifting the described bed frame, or its equivalent, from a substantially horizontal position, such as that in which it is shown in dotted lines in Fig. 1, 50 toward a substantially upright position, such as that in which it is shown in full lines in said figure, I may employ means such as a set of tension springs 37, shown as extending between the mentioned longer frame element 13' of the truck 11 and an angle element 33 extending parallel with the inner transverse frame element 30, and as secured at its ends thereto; and in order that a pivotal movement of the bed frame upon 55 the pins 28, or their equivalents, may be effective to impart movement to the described brace or lever 20, or its equivalent, I may use cam means of the general character best shown in Figs. 2, 3 and 4.

60 That is to say, connecting the bed frame

end and the mattress-retaining elements 30 and 35 by a short section or sections 38, 38' of angle iron, or the like, I may attach to one of these short sections, as to the side flange 39 of the section 38, a pair of cooperating cam fingers 40 and 41, that finger (40) which is more remote from the center of rotation which is provided by the pins 28 being the longer of the two, and the interval 75 between the mentioned fingers being substantially the same as the width of that curved portion of the arm 24 of the lever 20 which extends therebetween. The said fingers may be respectively provided with cam surfaces which incline backward and 80 downward in such manner that whenever the described bed frame is started from a substantially vertical position toward a horizontal position, the cam surface 42 of the finger 41, as said finger swings toward the 85 overarching head element 16, forces the arm 22 outward; and in such manner that whenever said bed frame is being swung from the substantially horizontal position shown in dotted lines in Fig. 1, and approaches a 90 vertical position, the cam face 43 of the longer finger 40 is effective automatically to produce an opposite movement, restoring the arm or lever 20 to its position of concealment beneath the truck 11, or its equivalent. 95

As will be appreciated from the foregoing, the mode of operation of the above described features of my invention is such that whenever the prospective user, having trundled the entire organization on its described 100 truck to an intended location of use, grasping the top or foot of the bed frame, starts to pull the same downward toward a horizontal position, the arm 22, provided with the mentioned rolling or gliding member 23, 105 is immediately forced outward,—this movement being initiated by the cam finger 41 and completed by the spring 35, although limited by such means as the engagement of the ball 26 within the cup or opening 27 or 110 by actual contact of one of the arms of the lever 20, as the arm 22 thereof, with a fixed stop, such as a stop 44 on the under surface of the frame member 13. The engagement 115 of the ball 26 within the socket 29 may advantageously be maintained (as by a helical compression spring, not shown, tending to press said ball outward) in order yieldably to retain the rolling or gliding member 23 in substantially the illustrated central position in front of the truck 11 or its equivalent, until the bed frame is again lifted almost to a vertical position,—the cam finger 40 being effective to retract the same only 120 as the bed frame approaches the last mentioned position.

Instead of using, in conjunction with the described parts, or their equivalents, a freely removable complete spring organization having an independent frame (which would 125

add unduly to the weight of the organization) I prefer to provide my novel beds with sets of springs permanently secured to bed frames of the general character above described. For example, as best indicated in Figures 1 and 5, I may secure to the bed frame elements 29, 29', or their equivalents, as by means of bolts or rivets 45, transverse spring-supporting members 46, which may be in the form of flat bars disposed edge-wise beneath rows of spiral springs, such springs being secured in any suitable manner to a secondary spring frame 49.

Although I have herein described a single complete embodiment of my invention, it should be understood not only that various features thereof might be independently used, but also that numerous modifications might be devised, by those skilled in the art to which this case relates, without the slightest departure from the spirit and scope of my invention, as the same is indicated above and in the following claims.

I claim as my invention:

1. In an organization of the general character described: a truck frame adapted to remain substantially horizontal while moved from place to place, as on casters; a bed frame pivotally connected therewith to permit shifting the same between an upright position of disuse and a substantially horizontal position of use; an arm adapted to engage the floor forwardly of the truck frame, said arm being mounted on and laterally movable relatively to said truck to prevent tilting thereof; resilient means tending constantly to throw said arm outward; and means on said bed for automatically moving said arm relatively to said truck whenever said bed is shifted between said upright position and said substantially horizontal position, said last mentioned means comprising camming fingers secured to said bed frame and adapted to engage an arm rigidly connected with the mentioned arm.

2. In an organization of the general character described: a truck frame adapted to remain substantially horizontal while moved from place to place, as on casters, a bed frame pivotally connected therewith to permit shifting the same between an upright position of disuse and a substantially horizontal position of use; an arm adapted to engage the floor forwardly of the truck frame and laterally movable relatively to

said truck to prevent tilting thereof; resilient means tending constantly to throw said arm outward; and means on said bed frame for automatically moving said arm relatively to said truck whenever said bed is shifted between said upright position and said substantially horizontal position, said last mentioned means comprising camming fingers secured to said bed frame and adapted to engage an arm rigidly connected with the mentioned arm and therewith forming a lever which is pivotally secured beneath said truck frame.

3. In an organization of the general character described, a truck frame, a bed frame pivotally mounted thereon, a floor engaging brace member pivotally mounted on said truck frame, and having an offset arm portion at one end, and means on said bed frame arranged to engage said offset arm portion and move the opposite end of said brace forwardly of said truck frame, during the movement of said bed frame from vertical to horizontal position.

4. In an organization of the general character described, a truck frame, a bed frame pivotally mounted thereon, a floor engaging brace member pivotally mounted on said truck frame, and cam means, projecting from the inner end of said bed frame, arranged to engage said brace member for automatically moving one end of said brace member inwardly and outwardly during final and initial portions of the upward and downward movements respectively, of the bed frame.

5. In an organization of the general character described, a truck frame, a bed frame pivotally mounted thereon, a floor engaging brace member pivotally mounted on said truck frame, means on said bed frame arranged to engage said brace member for automatically moving one end of said brace member outwardly from said truck frame during the movement of said bed frame from vertical to horizontal position, means on said bed frame for engaging said brace member, to give an initial inward movement of the brace member on raising the bed frame and resilient means tending constantly to throw said brace member outwardly.

In testimony whereof, I have hereunto set my hand at Los Angeles, California, this 12 day of September, 1925.

CHAS. LOFMAN.
